UNITED STATES PATENT OFFICE.

GEORGE G. F. BOSWELL, OF LAWRENCE, INDIANA.

FORM FOR SEWERS AND THE LIKE.

No. 870,269.

Specification of Letters Patent.

Patented Nov. 5, 1907.

Application filed February 14, 1907. Serial No. 357,354.

To all whom it may concern:

Be it known that I, GEORGE G. F. BOSWELL, of Lawrence, county of Marion, and State of Indiana, have invented a certain new and useful Form for Sewers and the Like; and I do hereby declare that the following is a full, clear, and exact description thereof, reference being had to the accompanying drawings, in which like letters refer to like parts.

The object of this invention is to improve the construction of sewer forms to make them more convenient to manipulate and to adjust them to sewers of various sizes.

The nature of the invention will be understood from the accompanying drawings and the following description and claims.

In the drawings Figure 1 is a transverse vertical section of a sewer and a sewer form in place, the latter being shown in side elevation and parts being broken away. Fig. 2 is a side elevation of a portion of the brace and means for securing its inner end in place, parts being broken away and the inner holder being shown by dotted lines. Fig. 3 is a transverse section of the brace and side elevation of the inner holder and the clamp, the holder being partly broken away. Fig. 4 is an elevation of the inner concave surface of one of the mold or form plates. Fig. 5 is a plan view of one of the braces with means at the outer end for engaging the mold or form plates. Fig. 6 is a longitudinal section of what is shown in Fig. 1, near one edge and through the inner holder and clamping plate.

In the first place, after the sewer trench has been dug, a concrete bottom 10 is put in place and upon that the form is erected. What may be termed two inner holders 11 are secured to two vertical posts 12. These holders are curved and extended so as to be nearly semicircular. They are made of T-iron and, therefore, have two flanges at right angles to each other. In the upper part of said inner holders there is a hole through which a rod or pipe 13 passes, said rod or pipe at its lower end entering the tubular post 12. Through holes 14 pins are inserted for fastening the parts 12 and 13 together. The upper ends of the holders 11 are connected by a turnbuckle 15, and the upper ends of the rods 13 are connected by another turnbuckle 16. By these turnbuckles said parts can be held in place and adjusted as needed. There is also a turnbuckle 17 at the lower end of the tubular posts 12, the ends of said turnbuckle being secured by the arms 18 to the lower ends of the inner holders 11. Threaded, caster rods 19 screw into the lower ends of the tubular posts 12, and rollers or casters are mounted on the lower ends of said rods 19. By turning those caster rods to the right the tubular posts 12 and the rods 13 may be forced upward to tighten and strengthen

the parts of the form. By turning said caster rods to the left, the tubular posts 12 and rods 13 may be lowered for adjustment of the parts of the form or to modify forms of sewers, or for the purpose of collapsing and removing the form. Braces 20 extend outward from the inner holders 11 in any desired number. They are likewise made of T-iron with a series of notches 21 along each side of the flange thereof which rests against the flat side of the inner holders 11.

The braces 20 are fastened in engagement with the inner holder 11 by the fasteners 22. These are triangular plates substantially as shown in Fig. 3, that fit astride the braces 20 and have projections 123 that extend into the notches 21 of the braces 20 and fingers 23 that project towards each other parallel with the fastener and clasp the edges of the inner holders, as seen in Figs. 1 and 2. Therefore, these fasteners 22 fit loosely on the holder 11 and after being located on the braces 20 are slipped longitudinally on the inner holder 11 into any desired position, and they may be removed therefrom when it is desired to modify the length of the braces 20. In that manner the braces 20 may be shortened to any extent so as to make a sewer form of the desired size. To the outer ends of the braces 20 there are secured plates 25 adapted to project through the slots 26 in the mold plates 27. On their outer ends said plates 25 have curved heads 28 centrally pivoted. A number of holes 29 are provided on the plate 25 to receive a pin 30 so as to secure the plate 25 adjustably to the brace 20, and the plates 27 are clamped between the head 28 and the end of the brace 20. The plates 27 overlap each other, the slotted edge of one plate overlapping the smooth edge of the adjacent plate. The plate 25 and head 28, therefore, bind the overlapping edges of the plates 27 together and hold them in position. The crown plate 130 is separate, resting upon the plates 27 on each side and upon the rods 13.

The plates 27 are concave, and their concavity is increased to adapt them to small sewers by two bars 31 with their adjacent ends overlapping and fastened together by a pin 32, and their outer ends being secured to the plate 27 so as to span said plate. By applying some force to the edges of the plate, it may be curved more and the curvature maintained and held by the bars 31 and pin 32. After the sewer form is placed, concrete 35 is deposited upon and about it, and when it hardens forms a sewer. After it has hardened, the sewer form is collapsed and removed.

What I claim as my invention and desire to secure by Letters Patent is:

1. A form for sewers and the like including a pair of segmental inner holders, radially extending braces with notched edges, fasteners for adjustably securing said

braces to the holders, said fasteners consisting of a plate extending over said brace with four extensions projecting through notches in said brace and overlapping said inner holder, and mold plates held in position by the outer ends 5 of said braces.

2. A form for sewers and the like, including a central form, outwardly extending braces, concave mold plates notched on one side with the notched edge of one plate overlapping the adjacent edge of the next plate, the outer 10 ends of said braces adapted to extend through said notches, and a pivoted head on the outer end of each brace adapted to clamp said plates against the end of the brace.

3. A form for sewers and the like, including a pair of 15 segmental inner holders, a pair of telescoping posts connected with the ends thereof, turnbuckles connecting the ends of the posts and also the ends of the inner holders

substantially as set forth, mold plates, and means extending from said inner holders for holding the mold plates in place.

4. A form for sewers and the like including a pair of segmental inner holders T-shaped in cross-section, a pair of vertical telescoping posts extending through one flange of each segmental holder near its upper end, turnbuckles connecting the ends of said posts and the ends of said 20 inner holders, a crown plate mounted upon the upper end of said posts, other concave mold plates, and means for holding said mold plates in place.

In witness whereof, I have hereunto affixed my signature in the presence of the witnesses herein named.

GEORGE G. F. BOSWELL.
